S. P. SPAIN

AUTOMATIC GRAIN FEEDER

Filed Oct. 14, 1926

Patented Oct. 11, 1927.

1,645,460

UNITED STATES PATENT OFFICE.

SYLVESTER P. SPAIN, OF ROCHESTER, NEW YORK.

AUTOMATIC GRAIN FEEDER.

Application filed October 14, 1926. Serial No. 141,598.

The object of this invention is to provide a new and improved automatic grain feeder for feeding fowls, etc.

Another object of the invention is to cause 5 the grain to be fed automatically at a predetermined time without human assistance other than setting the apparatus. Another object of the invention is to cause the apparatus to distribute the grain from one 10 source over a large area so that the grain will thereby be made accessible to a large number of fowls at the same time. This and other objects of the invention will be illustrated in the drawings, described in the 15 specification and pointed out in the claims at the end thereof.

In the drawings:

Figure 1 is a side elevation of my improved apparatus. 20 Figure 2 is a detail sectional view of the air control valve.

Figure 3 is a modification of the automatic feeding device.

Figure 4 is another modified form of 25 the automatic feeding device.

In the drawings like reference numerals indicate like parts.

Reference numeral 1 indicates a pan or 30 tray into which the grain is discharged and from which it is distributed. This pan is supported on an arm 2 which is pivoted on a bearing 3 to the bracket 4 provided on the upright 5. Above the pan 1 is provided a hopper 6 in which the grain is 35 stored. This hopper has a conical bottom 7 with an opening in the lower end of it through which the grain is discharged onto the pan 1. The pan 1 is normally held up so as to practically close this opening and prevent the flow of grain from the hopper.

On the upright 5 is provided a bracket 45 8 on which is provided a clockwork mechanism 9, which by an extra spring and suitable gearing drives a shaft 10 on which is placed a cam 11. The clock work and extra spring are wound up in any desired way similar to that used in an alarm clock. The shaft 10 and cam 11 are directly driven 50 by the extra spring similar to that used for driving the alarm mechanism of the alarm clock as referred to above. In this mechanism a suitable trip is used which is operated by the clock mechanism at any predetermined time to release the extra spring 55 which in turn causes the shaft and cam to

turn for the purpose that will presently be described. The details of the clock are similar to those found in ordinary alarm clocks, and constitute no part of my invention. The invention consists to some extent in the application of the alarm clock to the special mechanism which I have made. 60

The cam 11 engages with a lug 12 which is made integral with the pan 1. The high 65 part of the cam normally stands under this lug, and holds the pan in elevated position to close the opening of the bottom of the hopper and prevent the feed of the grain. At the predetermined time, the clock mechanism 70 releases the spring that drives the shaft 10 and causes the cam 11 to rotate. This permits the lug 12 and pan 1 to drop down uncovering the opening in the bottom 75 of the hopper and this permits the grain to flow into the pan. The lower end of the arm 2 engages with a valve 13 in the pipe 14. The pipe 14 communicates with the storage tank 15 in which air is held under 80 pressure. The air flows from this tank up through the pipe 14 to the nozzle 16 by which a blast of air is directed into the pan 1. The pipe 14 is normally closed by the valve 13. When the pan 1 drops because of its own weight, or because of the 85 added weight of the grain the lower end of the arm 2 moves the valve 13 and permits air to flow up through the pipe 14 and down through the nozzle 16. This air 90 blast blows the grain out of the pan and scatters it over a wide area as indicated by dotted lines. The shaft 10 continues to revolve driven by the clock work and at the end of a predetermined time, the cam 95 11 again lifts the pan 1 which in turn shuts off the flow of grain from the hopper and the arm 2 swings away from the valve 13 permitting a spring in the valve to close the valve and cut off the further flow of air. 100

In Figure 3 I have shown a modification of my feed in which the pan 1 is mounted on a stem 20 which slides in a socket 21 in a bracket 22. The clock 9 is supported below the pan and is provided with a cam 23 that 105 turns on a center 24 and engages a roller 25 on the bottom of the stem 20. As the cam turns the pan is pulled down to the full line position shown in Figure 3, and as the cam continues to turn the pan is released so that 110 the spring 26 raises it to the dotted line position. The stem 20 is provided with a cam

27 which engages with a pin 28 by which the valve 13 is opened for the air blast, when the pan is drawn down. When the pan 1 lifts again, the valve is released so that the 5 spring in the valve can close the valve.

The details of the valve are shown in section in Fig. 2.

In Fig. 4 I have shown a further modification in which the pan is held stationary 10 and in which the clock and cam are used to move an air valve at a predetermined time. In this case the grain is free to feed to the pan until the grain has piled up on the pan sufficient to stop the feeding. There- 15 after at a predetermined time the clock will operate to open the air valve and blow the grain off of the pan, and as fast as the grain is removed from the pan other grain will flow from the hopper to take its place, and 20 this operation will continue until the clock is operated to shut off the air blast, when the accumulation of grain on the pan will stop the feed.

I claim:

25 1. A poultry feeding device comprising a hopper, a concaved pan under the hopper on which the hopper is adapted to feed grain by gravity, means for blowing air into the concaved pan from above to blow the grain 30 deposited therein to the front and sides of said hopper and distribute it over a large area.

2. A poultry feeding device comprising a hopper, a concaved pan under the hopper 35 on which the hopper is adapted to feed grain by gravity, means for blowing air into the concaved pan from above to blow the grain deposited therein to the front and sides of said hopper and distribute it over a large 40 area; a cam for simultaneously lowering the pan and releasing the air blowing means.

3. A time feed distributing apparatus comprising a feed container supported in an elevated position and having an opening in 45 the bottom, a concaved pan mounted below

the opening of said container, a downwardly projecting nozzle projecting into said concaved pan and means for blowing air thru said nozzle into said concaved pan to spread the feed deposited in said pan from said container over a wide area in front and the sides of said container.

4. A time feed distributing apparatus comprising a feed container supported in an elevated position and having an opening 55 in the bottom, a concaved pan located below the open bottom of said container, means for raising and lowering said concaved pan a predetermined distance to open and close the open bottom of said container, a stationary nozzle above said concaved pan and behind the opening in the bottom of said container and means for blowing air thru said nozzle against the bottom of said concaved pan to blow grain deposited in said pan from said container and directing it upwardly thru curved sides of the pan to distribute the grain over a large area at the front and sides of the nozzle and the container.

5. A time feed distributing apparatus comprising a feed container supported in an elevated position and having an opening in the bottom thereof, a concaved pan mounted below said container, means for moving said pan in a vertical plane to alternately open and close the opening in the bottom of said container, means for supporting said concaved pan a predetermined distance from the open bottom of said container, to allow 80 a predetermined amount of grain to drop into said concaved pan, a nozzle located behind the bottom of said container and projecting angularly toward the bottom of said concaved pan, and means for controlling an air blast thru said nozzle into said pan on the movement of said pan.

In testimony whereof I affix my signature.

SYLVESTER P. SPAIN.
